UNITED STATES PATENT OFFICE.

HENDERSON MORTON POWERS, OF LANCASTER, PENNSYLVANIA.

DAMPER.

SPECIFICATION forming part of Letters Patent No. 619,342, dated February 14, 1899.

Application filed November 9, 1897. Serial No. 657,929. (No model.)

To all whom it may concern:

Be it known that I, HENDERSON MORTON POWERS, a citizen of the United States, residing at Lancaster, in the county of Lancaster and State of Pennsylvania, have invented 5 a new and useful Damper, of which the following is a specification.

My invention relates to an automatic draft-regulating damper that is under the control 10 of the operator.

Further objects and advantages of my invention will appear in the following description, and the novel feature thereof will be particularly pointed out in the appended claims.

15 In the drawings, Figure 1 is a plan of my automatic damper in position in a pipe, flue, or stack, appearing in section. Figs. 2 and 3 are longitudinal sections of the pipe, flue, or stack, showing the automatic valve in two 20 positions, one for day and the other for night, in a full side elevation. Fig. 4 is an end view of a pipe, flue, or stack, showing the automatic damper in a side elevation with the ring-plate in central section. Figs. 5 and 6 are plan 25 views showing a portion of the damper-plate and the key-handle, in combination with the trunnion, in a detached position.

Similar numerals of reference indicate corresponding parts in all the figures of the drawings.

30 In carrying out my invention I employ a main plate 1, which corresponds in design with the shape of the pipe, flue, or stack should they be round, square, or hexagonal. The plate 1 is provided at opposite points 35 with eccentric trunnions 7 and 8, which are mounted in suitable bearings 9 and 10 in the side of the pipe, flue, or stack and extend beyond the outer surface thereof. The eccentric trunnion 7 is cast or riveted to the main 40 plate 1, and the eccentric trunnion 8 is detached from plate 1 and is cast to the turning key-handle 11. The trunnion 8 has a slot through it to fit in a correspondingly-shaped 45 lug 12 cast to plate 1, and it is held to the plate 1 by a bolt 13, that passes through the slot in the eccentric trunnion 8 and through a hole in plate 1 and holds them securely together. The eccentric trunnion 8 can be detached 50 from plate 1 in a moment of time. Across the central opening of main plate 1 I insert a cross-bar 14, cast or riveted to plate 1. The design of this cross-bar 14 is a hole 15 in the center of cross-bar 14 to admit the stem of

valve 16 to pass through it, the valve 16 being smaller in diameter than the main plate 1 and being held to the valve-stem 17 by two jam-nuts 18, and the head 19 on the other end of valve-stem 17 will keep the valve 16 from becoming detached from cross-bar 14 and 55 valve 16 will work automatically through hole 15 in the center of cross-bar 14. When a gas explosion takes place, the valve 16 will rise and let the gas pass off through the pipe, flue, or 60 stack.

65 The gage-lugs 20, that are cast to the main plate 1 and shown in Figs. 2 and 3, are for the purpose of regulating the central opening of main plate 1 for night to let gas pass off through the pipe, flue, or stack and to keep 70 the valve 16 free from soot and smoke and to hold and regulate the fire as designed by the operator. The lug 21, that is cast to plate 1 and shown in Figs. 2 and 3 above the key-handle trunnion 8, is for the purpose of holding 75 the damper where it is wanted to be held by the operator.

70 In my invention of this automatic damper I get three distinct changes of draft—one for morning, one for midday, and one for night—80 and all under the control of the operator.

Having described my invention, what I claim is—

1. In a damper, the combination of a damper-plate having an opening therein, lugs on 85 one side extending at right angles to the face thereof, a disk adapted to rest on said lugs and to be moved therefrom, and means for limiting the movement of the disk away from the lugs.

90 2. In a damper, the combination of a damper-plate, a cross-bar having an opening in its center and extending across the opening in the damper, lugs extending from one surface of the damper, a disk adapted to rest on said lugs and to be moved therefrom, a rod secured to the disk and adapted to pass through the opening in the cross-bar, and means on the end of the rod to limit the movement of the disk, substantially as described.

95 In testimony that I claim the foregoing as my own I have hereto affixed my signature in the presence of two witnesses.

HENDERSON MORTON POWERS.
